UNITED STATES PATENT OFFICE.

FRANK A. BONHAM AND EVAN A. BONHAM, OF INDIANAPOLIS, INDIANA.

ROTARY SCREEN.

SPECIFICATION forming part of Letters Patent No. 780,098, dated May 17, 1904.

Application filed March 14, 1904. Serial No. 197,980. (No model.)

To all whom it may concern:

Be it known that we, FRANK A. BONHAM and EVAN A. BONHAM, citizens of the United States, residing at Indianapolis, in the county of Marion and State of Indiana, have invented certain new and useful Improvements in Rotary Screens, of which the following is a specification.

In the handling of coal from the mines it comes from the shaft mixed as to grades and size, and it is necessary to separate these grades in many cases before putting the coal into cars. This separation has heretofore been accomplished by means of long reciprocating inclined screens over which the coal passes, the finer sizes dropping through and passing to desired cars, while the larger sizes pass over the screens, and the largest size is the last to leave the screen at its farthest end. Such screens require for their support an exceedingly heavy and rigid tipple-building, and even then in the course of a few years the building becomes racked. Owing to the length of the screens it is also practically impossible to inclose them in such way as to prevent freezing of the wet coal during extreme weather, and the consequence is during such weather it is many times impossible to operate the tipple.

The object of our invention is to produce a screen structure capable of accomplishing the results already described, but of a totally different type and of such character that the larger sizes are the first to leave the screen structure instead of the last, and the screen structure is of such character that it may be readily inclosed in a building which may be heated during the winter, so as to prevent freezing.

The accompanying drawings illustrate our invention.

Figure 1 is a side elevation of a tipple-building constructed in accordance with our invention; Fig. 2, a plan; Fig. 3, a plan, on a larger scale, of our improved screen structure; and Fig. 4, a vertical section.

The screen structure consists of a central vertical shaft 10, supported in suitable bearings and driven by any desired means. Se-

veral superimposed conical screens 11, 12, 13, &c., any desired number being used and the coarsest screen being arranged at the top. Secured to the peripheries of these screens are hinge-pins 14, which are vertical and parallel with the shaft 10. Pivoted to each pin 14 is a gate 15, the free end of each of which is provided with suitable antifriction-rollers 16 and so arranged that its free end overlaps or comes closely adjacent the hinge-pin of the adjacent gate. These gates may be of any desired form, in the present drawings being shown as arched with the convex side toward the shaft 10. The gates 15 are normally held closed—*i. e.*, with their free ends closely adjacent or overlapping the next gate—by any suitable means—such, for instance, as circular tracks 17. These tracks 17 are opposite each cone 11, 12, 13, &c., interrupted for a short space, as clearly indicated at 18 in Fig. 2, and leading from this portion is a suitable trough or chute through which the coal may pass from the screen, so that as the shaft 10 is rotated in the direction indicated by the arrow the free end of each gate as it reaches the point 18 will be released from restraint and the coal on the screen will throw the gate open, as indicated in Fig. 3, and allow the coal to pass into the chute. The gates may be positively thrown up, making the tracks cam-shaped opposite each point 18, if desired. Continued rotation of the shaft 10 will cause the opened gate to have its free end brought into engagement with the opposite side of the trough and cause the gate to swing closed by contact with the track 17, the next succeeding gate being opened in the manner described.

The upper ends of the pins 14 may be supported by any suitable means, either by being made of such size as to have sufficient rigidity in themselves or by connection with a ring 19, resting upon the upper framework concentric with shaft 10 and driven by any suitable means—such, for instance, as sprocket 20, secured to shaft 10, counter-sprocket 21, chain 22, gear 23, secured to sprocket 21, gear 24, meshing therewith, sprocket 25, secured to gear 24, idler 26, and chain 27, passing over the sprockets 25 and 26 and partially embracing the periphery of ring 19, which is pro-

vided with suitable sprocket-teeth 28. By this means ring 19 may be driven at the same peripheral speed as hinge 14, and thus hold the upper ends thereof in proper position, so that the gates 15 may work freely.

It will be readily understood that the screen structure shown in Figs. 3 and 4 may be made of any desired capacity either in diameter or number of screens and that a discharge-trough will be led from a point opposite the periphery of each screen, said troughs being led to any desired points.

In Figs. 1 and 2 we have shown a three-screen structure in which suitable spouts are provided and led to points opposite four different car-tracks. The coal is delivered from the elevator (not shown) through a chute 29, which delivers into a suitable weighing-box 30, through which the coal may be discharged upon the upper screen-cone 18, the larger coal passing from thence through chute 31, while the smaller coal passes therethrough, the next size passing from screen 12 through chute 32, the next size passing from screen 11 through chute 33, and the finest size passing through screen 11 and being gathered by a hopper 34 and being delivered into a suitable carrier 35—as, for instance, a spiral conveyer—and delivered by it to the desired point.

It will be noticed by this arrangement that the screen structure may be inclosed readily and by the installation of a suitable heater this building maintained at such temperature as to prevent freezing, while the cars 31', 32', 33', and 35' may be arranged to pass upon each side of the structure, as shown.

It will be readily understood that the construction described, while being primarily designed for use in coal-mine tipples, is just as applicable to the separation of any materials, and it is to be understood that we do not desire to be limited to the use of our device.

We claim as our invention—

1. The combination, with a substantially vertical shaft, of a series of superimposed screens carried thereby and rotatable therewith, a series of gates arranged around the periphery of each screen and revolving there-

with to form an inclosing wall therefor, means for opening the gates in succession, and means for receiving the discharge from each of said screens at the point of opening of the gates.

2. The combination, with a substantially vertical shaft, of a series of superimposed conical screens carried thereby and rotatable therewith, a series of gates arranged around the periphery of each screen and revolving therewith to form an inclosing wall therefor, means for opening the gates in succession, and means for receiving the discharge from each of said screens at the point of opening of the gates.

3. The combination, with a substantially vertical rotatable shaft, of a series of superimposed screens carried thereby so as to rotate therewith, a series of vertical gates arranged around the periphery of each screen and revolving therewith and swingable upon substantially vertical axes to form an inclosing wall for each screen, means for opening the gates successively, and means for receiving the discharge from each screen.

4. The combination, with a substantially vertical rotatable shaft, of a series of superimposed screens carried thereby so as to rotate therewith, a series of vertical gates arranged around the periphery of each screen and swingable upon substantially vertical axes to form an inclosing wall for each screen, means for normally holding said gates in wall formation, means for opening the gates successively, means for receiving the discharge from each screen, a rotatable ring mounted above said screens and concentric therewith, said ring being attached to the upper ends of the pivots of said gates, and means for driving said ring in synchronism with the shaft.

In witness whereof we have hereunto set our hands and seals, at Indianapolis, Indiana, this 8th day of March, A. D. 1904.
